United States Patent Office.

JOHN LIMING, OF PHILADELPHIA, PENNSYLVANIA, ASSIGNOR TO HIMSELF AND CHARLES C. SAVERY, OF SAME PLACE.

Design No. 4,940, dated May 23, 1871.

DESIGN FOR A REFRIGERATIVE BUCKET.

The Schedule referred to in these Letters Patent and making part of the same.

I, JOHN LIMING, of the city of Philadelphia, in the State of Pennsylvania, have invented and produced a new and original Design for a Refrigerative Bucket, of which the following is a specification.

The nature of my design consists in the arrangement of a removable sheet-metal ice-retaining vessel centrally within a wooden bucket lined with sheet metal, and provided with a swinging bail and a removable cover, the object of my invention being the production of a portable refrigerator which may be readily and conveniently carried by hand, and at the same time serve effectually for preserving print-butter, meat, and such articles of food as require to be kept cool and fresh in hot weather, especially while being carried from the markets to dwellings, or to the retail provision-stores; and the said design is fully represented in and by the accompanying drawing, to which reference is made—

Figure 1 being a vertical central section of the said refrigerative bucket, and

Figure 2 a plan view of the same without the belonging covers of the bucket and ice-vessel.

A is a wooden bucket, having a removable cover, a', and the usual swinging bail a".

It is provided with an inside lining, a'', of tin-plate, and in the central portion of its bottom it has an annular flanch, 4, which supports, in a perpendicular position within it, a readily-removable sheet-metal can, B, which extends upward nearly to the cover a' of the bucket, and is fitted at its upper end with a readily-removable cover, b'.

C is a readily-removable skeleton frame, suspended horizontally around between the case B and the sides of the bucket, upon small brackets or studs, 5, which are soldered fast to the side lining a'', and serves as a dividing platform or shelf between the cover a' and the bottom of the bucket.

Claim.

I claim as my invention—

The design for a refrigerative bucket, substantially as described and shown.

JOHN LIMING.
